UNITED STATES PATENT OFFICE.

THOMAS BOYD, OF CLEVELAND, OHIO.

PACKAGE-TIE.

No. 882,863.

Specification of Letters Patent. Patented March 24, 1908.

Application filed September 20, 1907. Serial No. 393,836.

To all whom it may concern:

Be it known that I, THOMAS BOYD, a citizen of the United States, residing at Cleveland, in the county of Cuyahoga and State of Ohio, have invented a new and useful Package-Tie, of which the following is a specification.

This invention relates generally to package ties, and more particularly to one of that 10 class designed for use in the mail service for holding various kinds of mail matter securely assembled.

The object of the invention is to provide an article of this character which shall be 15 simple and durable in construction, easy to manipulate and certain of operation, and in which the binder shall be so secured around a package of mail matter that its accidental loosening or untying will be practically impossible, and in which, further, the cutting 20 of the binder by the tie plate will be obviated.

With the above and other objects in view, as will appear as the nature of the invention 25 is better understood, the same consists in the novel construction and combination of parts of a package tie, as will be hereinafter fully described and claimed.

In the accompanying drawings forming a 30 part of this specification, and in which like characters of reference indicate corresponding parts:—Figure 1 is a view in plan, exhibiting the package tie secured upon a package of mail matter. Fig. 2 is a perspective 35 detail view of the tie plate and a portion of the binder. Fig. 3 is a transverse sectional view taken on the line 3—3 of Fig. 1, and looking in the direction of the arrow thereon.

The tie comprises a plate 1 of resilient 40 metal, preferably, though not of necessity, flat and having a perimeter approximating that shown, the form herein exhibited having been adopted for the reason that it will be light and that irregular-shaped pieces of 45 sheet metal may be utilized in its manufacture, and thus materially lessen the cost of its production. Furthermore, by imparting to the plate the shape defined, there will be no sharp corners presented that might inflict 50 injury upon the person using the device, or that might mutilate mail matter. The plate is provided at what might be styled one corner with a key-hole shaped opening 2 in which is secured the binder 3 which, as usual, 55 consists of a length of any suitable cord, and that engages the neck of the opening.

The plate is provided with three binder locking members or tongues 4, 5 and 6, that are formed by being stamped from the plate in the usual manner, the slot of the opening 2 being disposed at right angles to the length of the tongues 4 and 5, whereby to cause the binder to assume a proper position relatively to the matter being bundled. These tongues are transversely dished away from the plate in order to prevent cutting of the binder, and are formed longitudinally on compound curves with their tips deflected away from the plate to present constricted entering throats for the binder. The spaces between the 60 tongues and the plate are somewhat less than the thickness of the binder to insure sufficient frictional grip with the latter to prevent slippage when the binder is being positioned around the mail matter. 65

As will be seen by reference to Fig. 1, the tongues 4 and 5 are disposed in parallelism and have their tips projecting in opposite directions, while the tongue 6 is obliquely disposed relatively to the said tongues and 70 has its tip projected towards the neck 7 of the opening 2, and its base or root 8 substantially in alinement with the inner edge of the tongue 5, although this is not essential. By disposing the tongues in the manner shown, 75 when the binder is being secured around the mail or other matter, there will be no interference presented by the tongues to the rapid and positive engagement of the binder therewith. 80

In using the tie, the binder is first secured in the neck of the opening 2. The mail matter having been properly arranged, the plate is placed on the upper side of the package at about its center, and the binder is 85 then passed transversely around the back of the package to its front, then is hooked in engagement with the tongue 6, thence is passed longitudinally along one end of the front of the package and around the back 90 thereof, thence along the other end of the front of the package, and is hooked into engagement with the tongue 5, thence passed over the latter tongue, and is finally hooked into engagement with the tongue 4 by which 95 it is firmly held. The locking of the binder is, however, effected at the tongue 5, as it will be seen that a bight or loop is formed in the binder at this point. To free the binder from the package, the reverse of the above 100 described operation is observed—that is to say, the binder is disengaged from the 105

tongues 4, 5 and 6, whereupon the tie plate with the attached binder may readily be removed.

The improvements herein defined, while simple in character, will be thoroughly effective for the purposes designed, and will result in the production of a practical and entirely reliable form of package tie.

I claim:—

10. A package tie comprising a flat plate having projecting from one side thereof a plurality of transversely dished longitudinally curved tongues, two of which are disposed in parallelism and with their tips projecting in

opposite directions, and a third locking tongue 15 disposed obliquely to the other two, the plate being provided with a keyhole-shaped orifice the slot of which is disposed at right angles to the two parallel tongues, and a binder secured in the slot of the orifice.

20

In testimony that I claim the foregoing as my own, I have hereto affixed my signature in the presence of two witnesses.

THOMAS BOYD.
